A. G. Burns ATTORNEY.

UNITED STATES PATENT OFFICE

IRVIN H. RIEKE, OF AUBURN, INDIANA, ASSIGNOR TO RIEKE METAL PRODUCTS CORPORATION, A CORPORATION OF INDIANA

BUNG AND SEALING MEANS

Application filed March 31, 1930. Serial No. 440,257.

This invention relates to improvements in a bung and sealing means for containers, and the object thereof is to provide a bung for closing the bung opening of a container and a seal applicable to the bung so constituted that after being applied to the bung, its removal therefrom, or removal of the bung from the container, cannot be accomplished without mutilating the seal.

10 Another object of the invention is to provide a bung and seal therefor so constructed that it may be applied to the bung instantly without recourse to tools or other equipment.

A preferred embodiment of the invention 15 is shown in the accompanying drawings, in which:—

Fig. 1 is a plan view of a bung fixture including a bung and seal applied thereto in which the invention is embodied, a portion 20 of the seal being broken away;

Fig. 2 is an elevation projected from Fig. 1, portions being broken away;

Fig. 3 is a side elevation of a seal partly 25 broken away showing a modified form of the invention, and

Fig. 4 is a similar view showing another modified form of the invention.

The illustrative embodiment of the invention comprises a cup-shaped bung 1 having an 30 externally threaded cylindrical wall 2 and a radial flange 3 extending outwardly from its top provided with a polygonal rim 4 that constitutes a wrench-head. The bung has a circular chamber 5 therein that is open at its top and which is accessible through said wrench-head. The bung is suited to be applied to the bung fixture 6 of a container 7 in the usual manner so as to close the opening 35 therein. The particular form of the fixture is immaterial to the present invention inasmuch as the invention is applicable to many of the well known types of bung fixtures. As an example, the bung fixture 6 shown in the drawings is secured in place in the shell of 40 the container 7, the flange 8 of said fixture being enveloped by and permanently secured in an embossment 9 formed in said shell.

The sealing means for the bung consists of 45 a shell 10 made of fragile sheet metal and shaped so as to have a cup 11 with a hollow

cowl 12 surrounding its upper end. The cup 11 is so proportioned as to telescopically fit 55 into the circular chamber 5 in the bung, and the cowl is so proportioned relative to the wrench-head 4 of the bung that it overhangs said wrench-head when the seal is in place and the outer rim 13 of the cowl is annular and encompasses the outer rim of the wrench-head without having normal contact therewith. A portion of the outer face of the rim 60 13, adjacent the top of the cowl, is preferably knurled so that the rim is susceptible to defacement when tampered with. The lower end of the cup has formed in its center an embossment 15 that extends through an opening 65 16 made in an anchor-plate 17, and the extreme lower end of the embossment is of greater diameter than the opening 16 so that detachment of the anchor-plate from the cup is prevented. The anchor-plate is preferably 70 triangular in form and presents three radially disposed jaws 18 equally spaced apart and which bear against the inner face of the cylindrical wall 2 of the bung when the cup of the seal is pushed into the chamber 5 there- 75 of. The anchor is proportioned with respect to the diameter of the chamber 5 in the bung so that the jaws 18 drag upon the cylindrical wall of the bung when the seal is applied thereto and cause the anchor to become dished 80 downwardly. The anchor 17 is preferably made of spring sheet metal so that when the anchor is forced into operating position it becomes sprung into locking engagement with the cylindrical wall of the bung and 85 thereby prevents withdrawal of the cup from the chamber.

In Fig. 3 is shown a seal of modified form in which the anchor 17' has an embossment 15' formed centrally therein that extends up 90 through the bottom of the cup 11' of the shell 12', the top of the embossment being enlarged so as to overhang the adjacent wall of the cup and thereby prevent detachment of the cup from the anchor.

In each of the forms shown in Figs. 2 and 3 the shell may have turning movement relative to the anchor-plate upon the axis of the embossment by which they are connected together without becoming detached.

In the form shown in Fig. 4 the anchor 17" is secured centrally to the bottom of the cup 11" by spot welding the anchor to the cup as indicated by 19. Or, the anchor 5 may be attached to the center of the cup in any other suitable manner as may be found convenient in manufacturing the seal.

In utilizing the invention, the container, after having been filled with the goods to be shipped, is closed by screwing the bung 10 into the bung fixture and tightening it by applying a wrench thereto. The seal is then applied to the bung by forcefully inserting the cup of the shell together with the anchor attached thereto into the chamber 5 of the bung. When the cup and anchor are thus positioned, the wrench-head of the bung is encased by the cowl and is thereby rendered inaccessible for the application of 15 a wrench or other means for applying force to unscrew the bung from the bung fixture. The shell being made of very fragile metal is susceptible to mutilation, and therefore, its removal from the bung can be accomplished 20 only with accompanying destruction or distortion of its cowl, or, by mutilating the connection between the anchor plate and cup, either of which conditions indicate that unauthorized removal of the bung has been 25 undertaken. In the event the cowl is compressed against the wrench-head so as to permit the application of a tool for turning the bung, the knurled rim of the cowl becomes mutilated and extremely difficult of 30 repair to such an extent as would conceal 35 the fact of such tampering.

What I claim is:—

1. In a bung for a container and sealing means therefor, the combination of a cup shaped bung having a wrench-head and a circular chamber opening through said wrench-head, and a sealing means comprising a fragile shell having a cup shaped to fit telescopically in said chamber and provided with a cowl at its top for encasing 40 said wrench-head when the sealing means is applied to said bung, and an anchor attached to the bottom of the shell cup having jaws that engage the wall of the bung cup 45 and lock the sealing means in place.

2. In a device of the class described the combination of a chambered bung having an opening through its head, a fragile shell having a bung head encasing part and a 50 central cup portion shaped to fit into the chamber of said bung, and a spring metal anchor secured to the bottom of said cup shaped portion having locking engagement 55 with said bung within the chamber thereof to 60 secure said shell in place.

3. A bung having a head and a circular chamber therein opening through said head, and a sealing means comprising a fragile shell having a portion adapted to telescopically fit into said chamber, and another con-

tiguous portion adapted to encase said head, and being provided also with an anchor attached to said first named portion adapted to have locking engagement with said bung within the chamber thereof and secure said 70 shell in place.

4. In a device of the class described, a chambered bung having an opening through its head, and a sealing means including a fragile shell and an anchor attached to the 75 bottom thereof by a destructible connection, and having locking relation with said bung in the chamber thereof, said shell being adapted to encase the head of the bung when the anchor is in locked connection with said 80 bung.

5. In combination with a bung having a head and a chamber opening through said head, an anchor adapted to have locking engagement with said bung when forcibly inserted into said chamber, and a fragile shell having a breakable connection with said anchor and shaped so as to encase the head of the bung when the anchor is in operative 85 position.

In testimony whereof I affix my signature.
IRVIN H. RIEKE.
